Primary Examiner — T. Chase Nelson*Assistant Examiner* — Mark Cavanna(74) *Attorney, Agent, or Firm* — Foley & Lardner LLP**CLAIM**

I claim the ornamental design for a plumbing fitting, as shown and described.

DESCRIPTION

FIG. 1 is a right, top, front perspective view of a plumbing fitting embodying my new design;

FIG. 2 is a right side elevational view of FIG. 1;

FIG. 3 is a left side elevational view thereof;

FIG. 4 is a front elevational view thereof;

FIG. 5 is a top plan view thereof; and,

FIG. 6 is a bottom plan view thereof.

The plumbing fitting is shown with a symbolic break in its length. The appearance of any portion of the article between the break lines forms no part of the claimed design.
